EWEN C. HENDERSON, OF PICTOU, CANADA, ASSIGNOR OF THREE-FOURTHS
TO JOHN MONROE, EDWARD CARSON, ALVAN J. CRAIG, AND JOHN
SMITH GRANT, OF PICTOU, NOVA SCOTIA, CANADA.

STITCH-FORMING MECHANISM.

SPECIFICATION forming part of Letters Patent No. 752,451, dated February 16, 1904.

Application filed December 23, 1902. Serial No. 136,819. (No model.)

To all whom it may concern:

Be it known that I, EWEN C. HENDERSON, a subject of the King of Great Britain, and a resident of Pictou, in the Province of Nova Scotia, Dominion of Canada, have invented a new and Improved Stitch-Forming Mechanism, of which the following is a full, clear, and exact description.

The object of this invention is to provide a stitch-forming mechanism for sewing-machines by means of which a lock-stitch may be formed without the use of a shuttle and its appurtenant parts.

To this end the mechanism comprises a needle carrying the needle-thread as usual, a guide adapted to carry a second thread to complete the formation of the lock-stitch, and a hook or other means for drawing the thread from the guide, these elements being constructed and arranged in a certain novel manner, as will hereinafter fully appear.

This specification is an exact description of two examples of my invention, while the claim defines the actual scope thereof.

Reference is to be had to the accompanying drawings, forming a part of this specification, in which similar characters of reference indicate corresponding parts in all the views.

Figure 1 is a side elevation of the mechanism. Figs. 2, 3, and 4 are front views showing the needle, the rotary hook, and the thread-guide in different positions and illustrating the formation of the stitch. Figs. 5, 6, and 7 are views illustrating a modification in which a reciprocating hook and cast-off are employed to produce the same result; and Fig. 8 is a vertical section of a sewing-machine, showing all of the parts concerned with my invention.

Referring to Figs. 1 to 4, *a* indicates the needle-bar carrying the needle *a'*, and *b* indicates the needle-thread. *c* indicates the thread-guide, which is here illustrated in the form of a rocking arm perforated to permit the lower thread to be passed through it. This lower thread is indicated at *e* in the drawings. *f* indicates a tension device for the lower thread, and *g* indicates a take-up,

which may be of the usual or any preferred form.

In Figs. 1 to 4 the hook *d* is shown to be of the usual rotary type driven from a shaft *h*, on which it is carried.

i indicates the needle-plate of the machine, and *k* may be taken to represent the fabric being stitched.

In the operation of the apparatus the needle descends and projects a loop of the thread *b* below the needle-plate. The hook *d* in rotating throws its bill through this loop of the needle-thread, and the thread-guide arm *c* assumes the position shown in Fig. 2, so that the bill of the hook *d* carries the lower or lock thread *e* and draws a loop thereof through the loop of the needle-thread. The needle now ascends, and concurrent with this action the loop of the needle-thread is drawn up tightly against the fabric, as in the usual manner. Fig. 2 shows the bill of the hook *d* entering through the loop in the needle-thread, and Fig. 3 shows the needle raised and the hook *d* continuing its rotary movement. As the hook reaches the position shown in Fig. 4, the above-described loop of the lower or lock thread *e* assumes the position there illustrated—that is to say, it lies slack over the bill of the rotary hook. The bill of this hook then again passes the guide-arm *c* and forms a second loop in the lock-thread *e*. Meanwhile the needle will have returned to its lower position and brought down a second loop in the needle-thread. The hook *d* then draws the second-named loop of the lock-thread through the loop of the needle-thread and also through the first-named loop of the lock-thread. It will therefore be seen that the first-named loop of the needle-thread is locked by the first-named loop of the lock-thread and that this first-named loop of the lock-thread is in turn locked by a second loop formed in the lock-thread. This second loop of the lock-thread is then drawn through the second loop in the needle-thread to lock said second loop, and a third loop is drawn from the lock-thread to lock the second loop of the lock-thread and also to lock the third loop of the

needle-thread. Thus the stitch progresses throughout the action of the machine.

The precise form of the means for drawing the lock-thread as above described is not material. Figs. 5, 6, and 7 show a reciprocating hook d' , working with a latch l and acting the same as the rotary hook. Figs. 5, 6, and 7 also show the various stages in the formation of the stitch the same as illustrated in Figs. 2, 3, and 4. It is also possible to form the stitch by means other than by reciprocating and rotary hooks. In this connection I will mention the oscillating hook. The illustration and description given herewith is thought to be sufficient to obviously suggest the application of this oscillating hook for the purpose in hand.

The needle-thread guide and hook are geared by suitable means to operate in the time or order above described. Fig. 8 shows an example of the various mechanisms which may be employed for this purpose.

Referring to Fig. 8, 10 indicates the table of the machine, and 11 the arm. 12 indicates the drive-shaft, having a cam-disk 14 attached thereto. Said cam-disk operates the take-up arm 15 and by means of a link 16 the needle-bar 17. 18 indicates a tension device coacting with the take-up 15 to carry the needle-thread b . Under the table 10 a rotary shaft 19 is arranged, this shaft being driven from the shaft 12 by means of a connecting-rod 20 and cranks 21. Said shaft 19 carries a cam 22, operating a sliding take-up 23, which coacts with a tension device 24 to control the lock-thread e . 25 indicates the sliding hook, having a latch 26 mounted thereon, these parts 25 and 26 being essentially the same as the elements d' and l in Figs. 5, 6, and 7. Said sliding hook 25 is operated by a cam 27 on

the above-mentioned shaft 19. A crank pin or screw 28 is carried by the end of the shaft 19, and this operates the oscillating thread-guide 29, which performs the functions of the element c in Figs. 2 to 7. Said thread-guide 45 is formed at its lower end with a slot 30, receiving a pin 31, carried by an arm 32, forming part of the framing of the machine. By giving the above-described parts the proper relative arrangement the needle-bar, the hook, 50 and the thread-guide may be caused to work in the proper time or order, so as to attain the results described hereinbefore.

Having thus described my invention, I claim as new and desire to secure by Letters Patent— 55

A stitch-forming mechanism, comprising the combination with a framing or support, of a needle adapted to carry the needle-thread, means for reciprocally driving the needle, a thread-guide adapted to carry a lock-thread, 60 a looper-hook, means for moving the thread-guide toward and from the path of the looper-hook, and means for operating the looper-hook, the said operating means of the needle, thread-guide and looper-hook being in connection with each other so as to operate in unison and to cause the hook to draw a loop of the lock-thread through a loop in the needle-thread and subsequently to release said loop of the lock-thread and draw a second loop of 70 the lock-thread through a second loop in the needle-thread and through the first loop of the lock-thread.

In testimony whereof I have signed my name to this specification in the presence of two sub- 75 scribing witnesses.

EWEN C. HENDERSON.
